UNITED STATES PATENT OFFICE

110,379

DESIGN FOR A FROZEN CONFECTION

Warren S. Watts, Montclair, N. J., assignor to Eskimo Pie Corporation, Bloomfield, N. J., a corporation of Delaware

Application March 19, 1938, Serial No. 75,971

Term of patent 14 years

To all whom it may concern:

Be it known that I, Warren S. Watts, a citizen of the United States, residing in Montclair, New Jersey, have invented a new, original, and ornamental Design for Frozen Confections, of which the following is a specification, reference being had to the accompanying drawing, forming part thereof.

Figure 1 is a front elevational view of a frozen
confection showing my new design;

Figure 2 is a top plan view of the same.

I claim:

The ornamental design for a frozen confection,
as shown.

WARREN S. WATTS.
